UNITED STATES PATENT OFFICE.

JOSEPH L. FIRM, OF JERSEY CITY, NEW JERSEY.

PRINTING-PRESS.

SPECIFICATION forming part of Letters Patent No. 650,639, dated May 29, 1900.

Application filed February 25, 1897. Serial No. 624,968. (No model.)

To all whom it may concern:

Be it known that I, JOSEPH L. FIRM, a citizen of the United States, and a resident of Jersey City, in the county of Hudson and 5 State of New Jersey, have invented certain new and useful Improvements in Printing-Presses, of which the following is a specification.

In my Patent No. 582,631, issued May 18, 10 1897, is shown a mechanism whereby a book or newspaper of sixteen pages may be formed, which mechanism consists in its most complete form of a web-printing mechanism adapted to perfect a web containing a plurality of pages abreast having the heads of adjoining pages in each transverse row pointing inversely to each other and transversely of the web, longitudinally-splitting mechanism, a longitudinally-folding mechanism for 15 each strip of the split web, guides whereby said longitudinally-folded strips are associated together and caused to travel in the same direction, mechanism whereby said strips are cut transversely into sections at the sides of 20 the pages on every other transverse margin, and mechanism for folding said sections on the intermediate transverse margins. For the mechanism shown in said patent a double-width press is necessary, and in view of 25 the fact that the page-columns run parallel with the axes of the cylinders in some cases such a press is objectionably wide.

As one feature of my present invention I am enabled to form a book or newspaper containing sixteen pages or more or less in which the page-columns are printed parallel with the axes of the cylinders by the employment of 30 a single-width press, or, in other words, one in which only two pages for a signature are 35 printed abreast on the same web.

As another feature of my invention I employ one of a plurality of printing mechanisms running at a slower speed than the others, whereby the web of said slower-running 40 mechanism, transversely severed into sections, is associated with the other web or webs in such manner that each section becomes a part of two signatures after the final transverse cutting.

Other features of my invention will be described, and pointed out in the claims.

In the accompanying drawings I have shown

a double-width press; but since each half on opposite sides of the longitudinal plane xx' prints and delivers separate products it is 55 evident that the half on either side of said plane may be used and considered as a single-width press, and I shall so treat it in the following description. It is shown as a double-width press for the purpose of showing 60 how the single width may, if desired, be duplicated.

Figure 1 is a plan view of the press with those portions omitted which are vertically above the tapes 34 and 38. Fig. 2 is a vertical longitudinal section of the same on line xx' of Fig. 1. Fig. 3 is an end view of the longitudinal and transverse cutting and folding mechanisms, partly in section. Fig. 4 is a detail of the manner of mounting the rollers, whereby the tension of the web is maintained against the impression-cylinders. Fig. 5 is a detail of the impression-cylinder by which the web is cut transversely. In Figs. 6 to 14 are shown the final products which 75 may be produced by the construction shown in Fig. 2, containing, respectively, ten, twelve, fourteen, sixteen, eighteen, twenty, twenty-two, twenty-four, and thirty-two pages; also, the positions on the webs in which the pages are 80 printed for said products, respectively. Fig. 15 shows a product containing twenty pages, with a line indicated at $x'x'$ on which, with my final folding mechanism, I may fold it 85 transversely across the pages after forming it into book form. Fig. 16 is a vertical longitudinal section of a modification of Fig. 2 in which the longitudinal folding is dispensed with. Fig. 17 shows the relative positions in 90 which the webs are associated by the construction shown in Fig. 16 for ten, fourteen, and sixteen pages, respectively. Figs. 18 and 18^a are end views of the driving-gear. Figs. 6^a and 6^b show the position of the sections of web C associated with another web.

Y, Y', and Y² are respectively the side members and base-plate of the frame upon which the printing-cylinders are supported.

A, B, C, and D are four webs of paper, and F, G, H, and I are the printing mechanisms 100 by which they are printed. The cylinders of each of these printing mechanisms are arranged, as shown, with the axes of the cylinders of each printing mechanism in a hori-

zontal plane and with the corresponding cylinders in the various printing mechanisms vertically above each other.

E is a former for longitudinally folding.

5 J is a carrier for transversely folding.

K is a longitudinally-folding and delivery mechanism of ordinary construction which may or may not be employed, depending upon whether it is desired to produce a fold across 10 the middle of the pages, as indicated by the line $x'x'$, Fig. 15, or otherwise.

Each of the form-cylinders carries four forms on a circumference, so that for each 15 rotation each form-cylinder when the press is single width will print eight pages, two by two. On form-cylinder 2 the four forms on the circumference are numbered 80 81 82 83. The pages of a signature are printed by every 20 semirotation of the form-cylinders.

25 By the construction shown in Fig. 16 a book or newspaper containing sixteen pages or less may be made. By the construction shown in Fig. 2 a book or newspaper containing thirty-two pages or less can be made by reason of the additional folding accomplished on the former E, which may double the size 30 of the product over its size where such longitudinal fold is omitted, as in Fig. 16.

Where the number of pages is a multiple 35 of four, all of the printing mechanisms will be run at the same speed and knives 30 and 30' will be omitted; but where the number of pages is not a multiple of four one of said printing mechanisms, as H, will be run at 40 half the speed of the other or others. To permit of this variation in the speed of one of said printing mechanisms, I make provision for using either a single gear for driving printing mechanism H from printing mechanism 45 G without change of speed, as shown in Fig. 18, or a compound gear to reduce the speed one-half, as shown in Fig. 18^a. In Fig. 16 the compound gear, composed of the small gear a and large gear a' , is shown in position 50 in dotted lines. In Fig. 2 the single gear a^3 is shown in position in dotted lines.

55 Since the combined radii of the two parts a and a' are equal to the diameter of the single gear a^3 , it is evident that they may be substituted for each other without changing the distance between the gears 7' and 11', but that in order to do so the position of the axis of rotation must be changed, so as to be midway between the gears 7' and 11' where the single 60 gear a^3 is used and so as to be nearer that gear with which the part a engages and farther from that with which a' engages where the compound gear is employed. This is provided for by the slotted bearing for said axis 65 shown at 107 in the frame-piece 106.

For a product of thirty-two pages I employ the construction shown in Fig. 2, with all the printing mechanisms running at the same speed. I print pages 2, 31, 15, and 18 from the 70 form-cylinder 2 and pages 1, 32, 16, and 17 from form-cylinder 4 on web A; pages 4, 29, 13, and 20 from form-cylinder 6 and pages 3, 30, 14,

70 and 19 from form-cylinder 8 on web B; pages 6, 27, 11, and 22 from form-cylinder 10 and pages 5, 28, 12, and 21 from form-cylinder 12 on web C; pages 8, 25, 9, and 24 from form-cylinder 14 and pages 7, 26, 10, and 23 from form-cylinder 16 on web D. The relative positions of said pages on the several webs are shown in Fig. 14. The four webs proceed to 75 the roller 22, the web A by passing around guide-rollers 19, 20, and 21, the web B by passing around guide-rollers 25 and 26, the web C by passing around guide-rollers 32 and 39, and the web D by passing around guide-rollers 46 and 47. Being collected at the roller 80 85 90 95 100 105 110 115 120 125 130 135 140 145 150 155 160 165 170 175 180 185 190 195 200 205 210 215 220 225 230 235 240 245 250 255 260 265 270 275 280 285 290 width webs B and D, but a half-width web C, as shown in Fig. 11. Web B receives pages 2, 19, 9, and 12 from form-cylinder 6 and pages 1, 20, 10, and 11 from form-cylinder 8. 5 Web D receives pages 6, 15, 7, and 14 from form-cylinder 14 and pages 5, 16, 8, and 13 from form-cylinder 16. Half-web C receives pages 4 and 17 from form-cylinder 10 and pages 3 and 18 from form-cylinder 12. The 10 arrangement of these pages upon the webs is shown in Fig. 11. The webs B and D, with the half-web C between them, are then collected, longitudinally folded and split, and transversely folded and cut, as before described for thirty-two pages.

For a product of twelve pages a full-width web A and a half-width web B are printed, with the arrangement of pages shown in Fig. 7. The web A is then longitudinally folded 20 and split, with the half-web B inside of it, and the whole is then transversely folded and cut in the same manner as before described for thirty-two pages.

I now come to numbers of pages which are 25 not multiples of four and which therefore require that one of the printing mechanisms, as H, should be run at half the speed of the others. The knives 30 and 30' on impression-cylinder 11 are used. Each knife cuts the 30 web transversely every time it passes the matrix on roller 32. These knives are prevented from cutting against cylinder 9 by the blanket-openings 9^a thereon and are prevented from cutting against cylinder 12 by the openings 35 12^a between the forms thereon.

For a product of ten pages I employ a full web B and a half-web C, as shown in Fig. 6. The web B receives pages 2, 9, 5, and 8 from one semicircumference of form-cylinder 6, 40 pages 2, 9, 3, and 6 from the other semicircumference of cylinder 6, pages 1, 10, 6, and 7 from one semicircumference of form-cylinder 8, and pages 1, 10, 4, and 5 from the other semicircumference of cylinder 8. The half-web C receives pages 4 and 7 from each semicircumference of form-cylinder 10 and pages 3 and 8 from each semicircumference of form-cylinder 12. The half-web C is now cut transversely on every other margin by serrated 45 knives 30 and 30', carried in diametrically opposite positions by the impression-cylinder 11 and coöperating with a matrix on the roller 32. Pins 31 on said cylinder 32 carry the forward edge of the web C between the rollers 35 and 32, where the tapes 33 and 34, running 50 at the same surface speed as printing mechanism H, assume control of it, and it is stripped from the pins by the strippers 32'. The rollers 35 and 32 are driven from the impression-cylinder 11 by the gears 11', 32', and 35'. Each section of the web C is then carried along by the tapes 33 and 34 (the tape 33 being driven by roller 35) until it meets the rollers 36 and 37, which are driven from cylinder 12 by gears 12', 100, 101, 102, 36', and 37' at the same surface speed as the web B or 55 at substantially-twice the surface speed of

the tapes 33 and 34. The distance between the bite of rollers 35 32 and the bite of rollers 36 37 is equal to at least the width of two 70 pages. The section of the half-web C is then carried onward between the tapes 38 and 61, driven by rollers 36 and 37, and between the rollers 39 and 40 and past the guide 62, and thence upward until it meets the web B at 75 the roller 22.

Any well-known construction of tapes (not shown) is provided for conducting the web D and the sections from web C from the guide 62 and roller 39 to the point at which 80 the sections enter between the webs B and D.

In Fig. 6^a I have shown the position in which the sections of web C will be associated with the web B at the roller 22, and in Fig. 6^b the position, including arrangement of 85 pages, after longitudinally folding web B around section C, but before transverse folding. The line v' is the position of the central margin between the pages on the section C and is the line on which the cut is made 90 which divides the paper between two signatures. The lines v and v² are where the transverse cuts occur at the other sides of said signatures. The lines w' w² are where the transverse folds occur in the middles of said signatures. Thus the paper included within bracket V' will belong to one signature and the paper included within the bracket V² will belong to another signature. One half of the section C will belong to the signature within 95 bracket V', and the other half will belong to the signature within bracket V². The transverse fold of the signature within bracket V' will occur at one edge, w', of the section C, and the transverse fold of the signature within 100 bracket V² will occur at the other edge, w², of section C. The web B and section C, combined as above described, proceed down the former E, so that the web is folded longitudinally outside of said section C. In one signature V' the leaf from section C containing 105 pages 3 and 4 lies between the first two leaves from web B. In the next signature V² the leaf from section C containing pages 7 and 8 lies between the last two leaves from web B, as 110 shown in Fig. 6^b. Just before leaving former E the web B is split by the knife e on the line w⁴, which lies in its central longitudinal margin and coincides with the edge of sections C. After being received upon the carrier J the 115 web is folded transversely on the lines w, w', w², and w³ at the edge of the section C through the folding-rollers u u' and is cut transversely on the lines v and v² midway between the sections C and on the line v' in the margin 120 at the middle of the sections C. In this manner two of the pages 7 and 8, comprising one leaf of each section C, become the inset (next to last leaf) of one newspaper or signature of ten pages and two of the pages 3 and 4, comprising the other leaf of each section C, become the inset (second leaf) of another newspaper or signature of ten pages. 125 130

In all cases where the sections C are em-

ployed the two leaves cut from each section will occupy positions in the final product at equal distances from the beginning and the end, respectively, of alternate products. I 5 do not limit myself to placing said leaves from section C always as the second and next to the last leaves, respectively, although that is where they are placed in the examples herein described and shown. The following pairs 10 of forms may be repeated on opposite semi-circumferences of the same form-cylinder—viz., the pair of forms whereby each side of web C is printed; also, the pair of forms whereby the first and last pages are printed; 15 also, the pair of forms whereby the second and next to the last pages are printed.

For a product of fourteen pages I use a full-width web B and two half-webs C and D. The arrangement of pages as printed by one 20 semicircumference of each form-cylinder employed is shown in Fig. 8. The relative position of the pages in the final products is shown in Fig. 8, in which figure M and M' represent the succeeding signatures which 25 are created from the webs by substantially the same mode of operation as described for the ten-page signature.

For a product of eighteen pages I use full webs B and D and a half-web C. The arrangement of pages as printed by one semicircumference of each form-cylinder is shown in Fig. 10. The relative position of the pages in the final products is shown in Fig. 10, in which N and N' are the successive signatures 35 produced from the webs by substantially the same manipulation as described for a signature of ten pages.

For a product of twenty-two pages I use full webs A and B and half-webs C and D. 40 The arrangement of pages as printed by one semicircumference of each form-cylinder is shown in Fig. 12. The relative arrangement of the pages in the final products is shown in Fig. 12, in which O and O' are the successive 45 signatures resulting from manipulating the webs in substantially the same manner described for a signature of ten pages.

In the modified form of construction shown in Fig. 16 the longitudinal folder is omitted, 50 and the webs associated between the rollers 21 and 22 proceed directly onto the carrier J. In this case the paper going to form each signature is equivalent in width to a half-web—that is to say, the pages for each signature on 55 each web are in single file. If the webs be more than half-width, they will be slit, and after being received upon carrier J each line of pages will be delivered as separate products.

60 In Fig. 17 I have shown the arrangement of the webs and pages thereon for signatures of ten, fourteen, and sixteen pages when delivered without longitudinal folding, as shown in Fig. 16. The arrow shows the direction 65 in which the webs move and the figures represent an edge view of the same. The trans-

verse cuts and folds occur as already described in connection with Fig. 6^a.

In printing-presses heretofore a large amount of attention has been requisite by 70 the operators to keep the tension of the webs leaving the web-holders such as to prevent slipping or fluctuations in speed or position of the web in being printed. I have invented a means by which this difficulty is overcome. 75

52 is a shaft journaled in the side frames of the machine and carrying the rollers or wheels 53 in such position as to engage the surface of the paper passing around the impression-cylinder 3 upon the unprinted longitudinal 80 margins on said paper or between and outside of the rows of pages. Shaft 52 is driven by gear 53' from gear 3' of printing mechanism F. These wheels clamp the paper firmly against the surface of the impression-cylinder, so that 85 the travel of the paper is obliged to correspond accurately with the speed of the cylinder-surface. To regulate the pressure of said wheels upon the paper, the bearings for the shaft 52 are made adjustable toward the center of the 90 cylinder 3 by the mechanism shown in Fig. 4, in which a set-screw 52^a bears against the block 52^b containing said bearings.

51 54 56 57 58 59 59^a are similar sets of adjustable rollers coöperating, respectively, 95 with the cylinders 1, 7, 5, 11, 13, and 15.

90 91 92 are mechanisms for applying paste, respectively, to webs A, B, and D.

In Fig. 18 is shown in elevation the arrangement of gearing by which the cylinders and 100 rollers of Figs. 1 and 2 are driven, the rollers with which the various wheels are connected being indicated by the use of the corresponding reference-figure with a prime, as 3', 4', 105 53', and 51', being wheels which are connected, respectively, with rollers 3, 4, 53, and 51. The wheels 100, 102, 104, and 105 are idlers which are used to transmit the motion between different parts of the press, and 101 is connected with the inking-roller H. It will 110 be observed that each series of wheels 53, 51, 115 54, 56, 57, 58, 59, and 59^a is driven with a surface speed corresponding with that of the impression-cylinder to which it is opposed. It will also be observed that the shafts 63 and 63^a are driven at a speed which causes the 120 wheels 36 37, fixed to said shafts, to drive the belts 38 and 61 at a speed corresponding with the forward travel of the webs A, B, and D. The wheels 36 and 37, over which the tapes 125 33 and 34 run, are revolvably mounted on the shafts 63 and 63^a, respectively, so that the belt 33 is free to be driven by the roller 35 and in turn to drive the belt 34 at a slower rate of speed than that at which the shafts 130 63 and 63^a are driven for the purpose of driving the tapes 38 and 61. The tape 38 by reason of running faster than the tape 33, due to its being directly driven through the gear 36', acts as a traction mechanism to propel the sections received by it forward at a greater rate of speed than that previously

given them. The surface speed at the point of contact between the wheels 36 and 37 may be increased above the speed of the tapes 38 and 61 by providing said wheels with peripheral flanges 36^b and 37^b, as shown, extending for only part of a circumference, which flanges will firmly grip each section and by suddenly accelerating will insure its complete separation on the proper line from the preceding section.

I claim—

1. In a printing-press, in combination, a plurality of web-printing mechanisms having printing-cylinders with substantially-parallel axes and adapted to print a plurality of webs each web containing two pages abreast having their heads pointing inversely to each other and transversely of the web, means whereby one of said printing mechanisms is run at a different speed from another, guides whereby said webs are conducted from said cylinders and associated without turning or reversing, a longitudinal folder, a slitter whereby said webs are slit on the central margin as they are being folded, mechanism whereby said webs are longitudinally folded and slit webs are cut transversely into sections at the sides of the pages on every other transverse margin and mechanism for folding said sections on the intermediate transverse margin substantially as described; whereby said webs receive their primary fold together at the ends of the pages and their final fold inside of each other on every other transverse margin at the sides of the pages and between consecutive pages.

2. In a printing-machine, in combination, a plurality of printing mechanisms each adapted to print a web with the page-columns running transversely of the web, mechanism whereby one of said webs is cut transversely into sections on every other transverse margin, mechanism whereby said sections are combined with the web from another printing mechanism in such manner that the pages on a section register with pages belonging to two signatures on said web, mechanism whereby said combined web and section are cut transversely on the margin at the middle of said section, and mechanism whereby said web is folded transversely outside of the half of said section on the margin at the edge of said section, substantially as described.

3. In a printing-machine, in combination, a plurality of printing mechanisms adapted to print a plurality of webs with the page-columns running transversely of the webs, one or more of which webs contains two pages abreast having their heads pointing inversely to each other, mechanism whereby one of said webs is cut transversely into sections on every other transverse margin, mechanism whereby said sections are combined with another web in such manner that the pages on a section register with the pages belonging to two signatures on said web, mechanism whereby said web is longitudinally folded outside of said

section, mechanism whereby said combined web and section are cut transversely on the margin at the middle of said section and mechanism whereby said web is folded transversely on the margin at the edge of said section, substantially as described.

4. In a printing-press, in combination, a printing mechanism for web B each form-cylinder of which contains on each semicircumference four-page forms for a single signature, two forms lying transversely of the web in each quarter-circumference with heads pointing inversely, a printing mechanism for web C, mechanism whereby web C is cut transversely into sections on every other transverse margin, mechanism whereby said sections are combined with said web B in such manner that the pages on each section register with pages belonging to two signatures on said web, mechanism whereby said associated web and sections are cut transversely on the margin at the middle of each section, and mechanism whereby a signature from said web is folded transversely outside of each half of each of said sections, substantially as described.

5. In a printing-machine, in combination, the following mechanism whereby are made from a plurality of webs two signatures in which one of the webs supplies pages alternately for the first and last half of said signatures, viz: a plurality of web-printing mechanisms, mechanism whereby one of said webs is cut transversely into sections each containing a leaf for each of two signatures, mechanism whereby each section is associated with a web so that said section registers with the leaves on said web of two signatures, mechanism for cutting the webs and sections on the margins between the signatures and mechanism for folding the signatures on the margins at the edges of the sections, substantially as described.

6. In a printing-machine, in combination, a plurality of printing mechanisms each adapted to print a web with page-columns running transversely of the web, mechanism whereby one of said printing mechanisms is driven at a slower speed than another, a cutting mechanism whereby said slower-running web is cut transversely on every other transverse margin as it leaves its printing mechanism, tape mechanism, as 33, driven at substantially the speed of said slower-running printing mechanism receiving said slower-running web after being cut and having a supporting-surface substantially as long as the width of two pages, web-traction mechanism as 38 driven at substantially the speed of said faster-running printing mechanism whereby the sections of said transversely-cut web are conveyed from said tape mechanism 33 to a point of association, substantially as described.

7. In the conveying mechanism of a printing-machine, a sheet-accelerator containing the following parts in combination, viz: the

tapes 34 and 38, mechanism whereby the same are driven so that the tape 38 runs at a greater speed than the tape 34, the wheel 36 carrying the tape 38, the wheel 36^a carrying the 5 tape 34 and web-biting mechanism 36^b, 37^b; said wheels 36 and 36^a being in axial alignment and said biting mechanism having a pe-

ripheral speed exceeding that of the tape 38, substantially as described.
